ANGELOS McCLARA, OF WHITNEY'S POINT, NEW YORK.

Letters Patent No. 83,692, dated November 3, 1868.

IMPROVED POST-DRIVER.

The Schedule referred to in these Letters Patent and making part of the same.

To all whom it may concern:

Be it known that I, ANGELOS McCLARA, of Whitney's Point, in the county of Broome, and State of New York, have invented a new and useful Improvement in Post-Driver; and I do hereby declare that the following is a full, clear, and exact description thereof, which will enable those skilled in the art to make and use the same, reference being had to the accompanying drawings, forming part of this specification, in which—

Figure 1 is a side elevation of my invention, and

Figure 2 is a rear view of the ram and its elevating-frame.

Figures 3 and 4 are detail views.

Similar letters of reference indicate like parts in all the figures.

In the accompanying drawings, A is an ordinary wagon, on the rear end of which are mounted the elevating-frame and ram B C.

The ram C is operated in such manner that the delivery of the blow is always under the immediate control of the operator, who is stationed at the post; and the parts are so constructed that the horses or elevating-power cannot deliver the blow, as ordinarily. To do this, the elevating-rope F is fixed to the ram in a permanent manner, as shown by fig. 2, and the frame B is provided with a spring-latch, f, which engages with a notch, e, in the ram, when it is elevated, and this prevents the return of the ram until the blow is wanted, when it is delivered by the operator pulling the tripping-line g. As soon as the latch f engages with the ram, the team backs up again at once, and is ready to go ahead as soon as a blow is struck. When the team has backed up, the rope F is slackened under the wagon sufficiently for the fall of the ram.

This method I have found to give desirable advantage over the self-discharging ram, as, in starting the posts into the ground, I steady them by hand for the first blow, and by this means the blow can be delivered at the moment it is wanted, without having to wait, and without liability of having blows delivered before they are wanted; and the team can begin to back up at once after a hoist, whether the operator is ready for a blow or not, and the backing up of the team during momentary delays is so much time saved, as they are ready to start ahead immediately after a blow which follows said delays.

The spacing of distance between fence-posts is done by the chain h, which is secured to the last post, J, fig. 1, as ordinarily, so that the wagon moves the same distance forward at each movement. But instead of

placing the chain around the post J, I attach that end of the chain near to one end of a lever, K, fig. 3, and then provide the long arm of this lever with a spike, k. This lever K is attended to by a boy, who places its short end behind the last post, and pushes the spike into the ground, and by this means stops the wagon at the proper distance. And when the last blow on a post is delivered, and the wagon is to start ahead, no time is lost in releasing the chain, as, when the lever is taken up, the spike k is pulled out of the ground and the chain released at once.

The pole or tongue of the wagon is made in two parts, M m, the lower part, m, sliding longitudinally under the main tongue, M, in guides n n.

The base of the tongue is provided with a self-engaging bolt, l, for securing the sliding tongue, m, to the main tongue, M, when desired; but this bolt is thrown up out of action by placing a wedge under its elevating-lever L when driving posts; and its use is not necessary when drawing the wagon forward from the position of one post to the next, as the weight of the ram C, acting through the rope F, is sufficient to hold the tongue m back while the vehicle is being moved forward to a new position. But when the wagon is being transported from place to place, or used for other purposes, then the bolt l is allowed to engage with the lower tongue. The team is attached to the lower tongue, (p, fig. 1, representing the double-tree,) and is thus always equally ready to hoist the ram or proceed with the wagon, as desired. The chain h being fast, the ram is hoisted, and, when released, the wagon moves forward, to take up a new position.

The ram C is made of wood, and is sawed out of the body of a birch-tree.

By these means I obtain a simple and very efficient apparatus.

Upon actual trial, I have with this apparatus driven thirty fence-posts in twenty-four minutes, doing the work in a good and substantial manner.

Having thus described my invention,

What I claim as new, and desire to secure by Letters Patent, is—

The combination of the secondary sliding tongue m with the ram C B F and wagon A, as and for the purpose set forth.

The above specification of my invention signed by me, this 23d day of July, 1868.

ANGELOS McCLARA.
